UNITED STATES PATENT OFFICE.

FREDERIC WILLIAM LEEVERS, OF HORNSEY, ENGLAND.

VALVE.

1,414,141.

Specification of Letters Patent. Patented Apr. 25, 1922.

Application filed September 19, 1921. Serial No. 501,807.

To all whom it may concern:

Be it known that I, FREDERIC WILLIAM LEEVERS, a subject of the King of Great Britain, residing at 60 Park Avenue North, 5 Hornsey, N. 8, England, have invented certain new and useful Improvements in Valves, of which the following is a specification.

This invention relates to improvements in 10 valves for steam, gas, water or the like of the type in which the closing member consists of a pair of discs which are raised and lowered by means of a carrier attached to a valve spindle, the discs being forced apart 15 when the carrier is in, or approaches, its lowest position so as to cause them to seat themselves firmly over the entrance and exit of the valve chamber. Firstly such valves have hitherto been proposed in which the 20 discs rotate after reaching a position in line with the centres of the exit and entrance while they are being forced apart so as to seat themselves with a concentric bedding action. This has been accomplished by providing a boss on the inner side of each valve 25 disc the two bosses being provided with helically engaging surfaces adapted to slide over each other so that the discs rotate owing to eccentric pins on the valve discs 30 engaging slots in the carrier and acting as cranks which are turned during the downward movement of the carrier. Secondly such valves have also been proposed in which the two discs are forced on to the 35 valve seats by means of wedge arrangements but without any means for rotating the discs when these are in a position concentric with the bore of the valve.

The object of the present invention is to 40 improve and simplify the mechanism of the first mentioned type of valve and to provide means whereby the discs while being thrust on to the seats are given a concentric bedding action in the second mentioned or 45 wedge operated types of valves and to that end it consists in providing a rounded or conical shaped boss on the inner side of each valve disc and making integral with or securing to the carrier a wedged shaped 50 member adapted to move between these rounded bosses and to force the discs apart, eccentric pins or projections of round oval or other suitable section of the requisite strength being provided as before on the in-

ner sides of the discs engaging slots formed 55 in the carrier so that the discs are rotated while the wedge is being forced between the rounded bosses and the discs are forced on to their seats and rotate simultaneously.

The accompanying drawings illustrate one 60 method of carrying this invention into effect; Fig. 1 being a sectional side elevation through a valve, Fig. 2 is a sectional plan, Fig. 3 is a sectional end elevation and Fig. 4 a sectional view of a modified form of 65 valve.

In carrying my invention into effect according to the modification illustrated in Figs. 1 to 3 I provide a pair of discs 1 having projections 2 (Fig. 3) on the periphery. 70 On the inner side of each disc I provide a central boss 3 with a conical or spherical surface and eccentric pins 4 located preferably partly on the disc and partly on one of the projecting portions 2. The carrier 5 75 may be formed integral with or may be secured to the valve spindle 6 and is provided with a central recess containing a wedge shaped member 7 which projects between the two bosses 3 formed on the discs. The 80 carrier is also provided with arms 8 in which are formed slots which are slightly larger than the eccentric pins 4 so that there is some lost motion between the pins and the 85 slots. When closing the valve the discs 1 are prevented from rotating owing to the plane surface of the valve disc in contact with the guides 9 formed in the valve casting between which they slide and can only 90 rotate when they reach their lowest position with their centres in line with the centres of the entrance and exit to the valve chamber. When this position is reached the 95 projections 2 on the periphery of the valve disc have left the lowest point of the plane surface of the guiding members 9 and may now enter the circular part of the guide, since the arc bounding the projections 2 and the circular part of the guide are arcs of concentric circles, the former of a slightly 100 smaller diameter to allow sufficient clearance for rotation so that a further movement of the valve spindle 6 causes the carrier to descend thereby forcing the wedge shaped member 7 between the bosses 3 on the valve 105 discs and causing them to move apart. At the same time the pins 4 are engaged by the slots in the arms 8 of the carrier 5 in-

roducing a turning movement about the axis through the center of the discs thus causing the discs 1 to rotate so that as they are forced apart and on to their seats they 5 do so with a rotary bedding action.

In opening the valve, owing to the lost motion between the pins 4 and the slots, the wedge shaped member 7 is slightly withdrawn before the underside of the slots engage 10 the pins 4 thereby releasing the pressure from the valve faces before there is any tendency for the discs to be rotated. This prevents any possibility of jamming or of causing the discs to score or otherwise damage 15 the valve seats, further the discs complete rotation before they move from the central position.

In the modification illustrated in Fig. 4, I may do away with the lower projections on 20 the discs and provide one or two thrusters or stops 10 which hang loosely in the carrier 5 until the discs take up a position central with the bore of the valve, when in this position these thrusters arrest further downward movement of the discs and act as fulcrums upon which the discs rotate.

What I claim as new and desire to secure by Letters Patent of the United States is:—

1. In a valve, the combination of a valve 30 casing, a valve disc, an operating spindle, a guide for preventing rotation of said valve disc during a predetermined downward movement, a valve disc carrier, means associated with said valve disc for arresting its downward movement, and means connecting the carrier and valve disc for rotating the said disc during the seating operation.

2. In a valve, the combination of a valve 40 casing, a valve disc, an operating spindle, a guide for preventing rotation of said valve disc during a predetermined downward movement, a valve disc carrier having an arm, integral projections extending along a part of the periphery of said valve disc for 45 arresting its downward movement, and means engaging the disc carrier arm with

the valve disc for rotating the said disc during the seating operation.

3. In a valve, the combination of a valve casing, a valve disc, an operating spindle, a 50 guide for preventing rotation of said valve disc during a predetermined downward movement, a carrier having a wedge shaped valve disc operating portion, longitudinal of the operating spindle interposed between the 55 valve discs for imparting lateral displacement simultaneous with the rotary seating operation during a straight line movement of said carrier, means associated with said valve disc for arresting its downward movement, and means connecting the carrier and valve disc for rotating the said disc during the seating operation.

4. In a valve, the combination of a valve 60 casing, valve discs, means associated with said valve discs for arresting their downward movement, a guide for preventing rotation of said valve discs during a predetermined downward movement, a carrier having a wedge-shaped valve disc operating portion interposed between the valve discs for 65 imparting lateral displacement simultaneous with the rotary seating operation at the ultimate downward travel of said valve discs during a straight line movement of the carrier, a valve disc carrier arm having openings on opposite sides, and means connecting the carrier arm and valve disc for rotating 70 said discs.

5. In a valve, the combination of a valve 75 casing, a valve disc, an operating spindle, a guide for preventing rotation of said valve disc during a predetermined downward movement, a valve disc carrier having an arm, means associated with said valve disc 80 for arresting its downward movement, and a lost motion connection permitting the valve disc to be released from its seat before rotation of the valve disc on opening the valve.

In witness whereof I have hereunto set my hand this 5th day of September 1921.

FREDERIC WILLIAM LEEVERS.
